UNITED STATES PATENT OFFICE.

PERLEY R. GLASS, OF BROOKLINE, MASSACHUSETTS, ASSIGNOR TO P. R. GLASS COMPANY, OF BOSTON, MASSACHUSETTS, A CORPORATION OF MASSACHUSETTS.

FOLDING-MACHINE.

1,346,195.

Specification of Letters Patent. Patented July 13, 1920.

Application filed May 14, 1917. Serial No. 168,482.

To all whom it may concern:

Be it known that I, PERLEY R. GLASS, a citizen of the United States, residing at Brookline, in the county of Norfolk and State of Massachusetts, have invented certain Improvements in Folding-Machines, of which the following description, in connection with the accompanying drawings, is a specification, like reference characters on the drawings indicating like parts in the several figures.

This invention relates to folding machines and is herein illustrated in connection with a machine for folding the edges of pieces of upper leather preparatory to incorporating them in boots and shoes.

In folding machines as hitherto constructed, the material has been fed past a stationary folder or one held from movement in the line of feed in order to form the fold; and commonly the material has been fed past a stationary folder having the form of a plow. In some types of folding machines this has necessitated the reciprocation of comparatively heavy parts, such as the pressing members, in order to feed the material: in others it has necessitated a combined creaser and feed member which moves past the plow during the formation of the fold. Both of these constructions have disadvantages; the first, the vibration and wear due to the weight of the moving parts; the second, the changing relation between the folder and creaser.

According to one feature of the present invention a creaser and a folder are moved intermittently backward along the edge of the material to form the fold while the material is being held stationary by the fold presser. By thus moving the folder and creaser, which may be elements of small weight in the line of feed, the necessity which exists in some machines for reciprocating the comparatively heavy presser members is obviated. And by causing the creaser and folder to move in unison their relation to each other remains unchanged during the fold forming operation.

These and other features of the invention including certain details of construction and combinations of parts will be described in

connection with an illustrative machine and pointed out in the appended claims.

Referring to the accompanying drawings,—

Figure 1 is a perspective of a machine in which the present invention is embodied;

Fig. 2 is a perspective showing more particularly the mechanism for actuating the feeding, folding and pressing mechanisms;

Figs. 3 to 6 inclusive are perspectives of the feeding, folding and pressing members in different positions, Figs. 3 to 6 showing the material in process of being fed, folded and pressed, and

Fig. 7 is a detail, partly in section, showing more particularly the mechanism for raising and lowering the lower feed member.

Before proceeding to a detailed description of the machine, a short explanation of its mode of operation will be given. Referring more particularly to Figs. 3 to 7, the material to be folded is supported on a table 9 upon which is fastened a stationary anvil

11 having an inclined face. A hammer 13 having a complementary face is oscillated toward and from the anvil at the proper time to press the fold and to hold the material while the feeding and folding means, presently to be referred to, moves back to grip the material preparatory to feeding it forward. The feeding means comprises an upper feed member and creaser 15 and a lower feed member 17, said lower member

being raised and lowered intermittently at the proper times to grip and release the material; and the folding means is a plow 19. The feeding means and the plow are mounted on a slide 21 (see Fig. 2) and all

of the members of the feeding and folding means are moved backward and forward together as the slide is moved. Starting with the parts in the positions shown in Fig. 3,

the upper feed member 15 is raised by depressing the finger-piece 23, and the work is placed in position as shown in Fig. 4. The feeding and folding means then move forward into the positions shown in Fig. 5

which brings the forward part of the fold beneath the hammer. The hammer then descends, as shown in Fig. 6, and the lower

feeding member 17 is lowered to release the grip of the feeding means upon the work. While the work is held by the hammer, the feeding and folding means are moved back, 5 whereupon the lower feeding member 17 and the hammer 13 are raised, and the parts are once more in the position shown in Fig. 4. During the forward movement of the feeding means and plow, the work is fed; during 10 the rearward movement the margin of the work is folded or turned over by the plow as it is drawn along the edge of the material. With this brief description of the 15 operation of the machine the details of its construction will now be described.

The moving parts of the machine which have been described above receive their motion from a driving shaft 25 having eccentrics thereon two of which are shown at 20 27 and 29. The eccentric 27 oscillates a forked lever 31 about the axis of a stationary shaft 32, said lever being connected through a yoke 39 and spring 33 with the stem 35 of the hammer 13, said stem being 25 pivoted at 37 to the frame of the machine. The spring 33 surrounds the stem of the yoke, a thumb nut 41 serving to vary the tension of the spring and consequently the pressure of the hammer upon the work. 30 The eccentric 29 oscillates a forked lever 43 which is mounted similarly to the lever 31 and is connected with the lower feeding member 17 through a yoke 45 and spring 47. The feeding member is carried at one end 35 of an arm 49 which is pivoted at its other end to the slide 21, the yoke 45 extending up through a slot in the slide and being pivoted at its upper end to the arm 49. Its stem extends through a bracket 51, which 40 may be adjusted to vary the tension of the spring, and through a guide formed on the side of a block 53 which is pivoted at 55 to the forked lever 43. By loosening the locking screw 57 and turning the adjusting screw 59 the bracket 51 may be raised or 45 lowered to vary the tension of the spring 47.

A third eccentric (not shown) on the shaft 25 oscillates a third forked lever 61 which is connected by levers as shown with 50 the slide 21. This lever and its connection to the slide is practically identical with the construction shown and described in British Patent No. 15,405 of 1912 and will not be described further except to point out that 55 adjustment of a block 63 in a slot in the lever 61 by means of a fork 65 varies the extent of movement of the slide 21, said adjustment and variation being possible during the operation of the machine.

60 A fourth eccentric 67 on the shaft 25 is connected by suitable mechanism with a snipping knife 69. In the present machine the stem of the knife is pivoted at the end of an overhanging arm 71 while in the machine of the British patent the knife is piv- 65

oted at a point beneath the work table. Otherwise the two constructions are substantially the same and no further description of the present construction will be given other than to explain that the knife 70 is normally inoperative but may be vibrated at any time by depressing a treadle (not shown) which pulls the bar 73 to the left as viewed in Fig. 1. The details of construction and mounting of the knife mechanism, as well as those of the slide 21, and the inclined hammer and various other features herein shown form no part of the present invention but are claimed in United States Patents No. 1,281,555, granted Oct. 80 15, 1918, and No. 1,270,753, granted June 25, 1918, on applications filed by me.

In the machines of these prior patents the hammer and anvil move with the slide 21 to feed the work. In the present machine the anvil is stationary and the hammer has no movement in the line of feed. Instead the plow 19 and the member 15 are mounted upon the slide and move backward and forward with it. The plow is 90 fastened to the slide by a screw. The member 15 is mounted in a head 75 which is fastened to the slide 21. The mounting of the member 15 in the head 75 is substantially the same as that of the British patent, 95 and the details of construction are claimed in my prior United States patents which have been referred to. For the purpose of describing the present invention it is necessary to explain merely that the member is held in the position shown by a spring but may be raised to permit presentation of the work by depressing the finger piece 23. It should be understood that while in my prior machines the member 15, or what has corresponded to the member 15, has acted merely as a creaser to determine the line of the fold, in the present machine this member is a combined creaser and upper feed member.

A general description of the operation of the machine has been given above and need not be repeated. It will be clear now that the combined upper feed member and creaser 115 together with the plow 19 move forward and back with the slide 21, and that the lower feed member 17 has in addition an up and down movement to grip and release the work at the proper times. The mechanism for moving the slide 21 and for varying the extent of its movement is so constructed and arranged that the limit of the forward movement of the slide is always the same. That is, the plow comes to rest in its forward position always at the same point. This is desirable in that it keeps the folding instrumentalities near together when the feed is shortened to go around small curves; and further in that it permits the back of the plow to be used as a shear 125 130 135

member in coöperation with the vibrating knife 69.

Although the invention has been set forth in connection with a particular machine it should be understood that the invention is not limited in the scope of its application to the particular machine which has been shown and described.

Having thus described my invention, what I claim as new and desire to secure by Letters Patent is:

1. A machine of the class described, having, in combination, a support for a piece of flexible material, a creaser, a folder, and means for moving the creaser and folder backward along the edge of the material and in contact therewith to form the fold.

2. A machine of the class described, having, in combination, a support for a piece of flexible material, a creaser, a folder, means for moving the creaser and folder backward along the edge of the material and in contact therewith to form the fold, and means for pressing the fold.

25 3. A machine of the class described, having, in combination, a support for a piece of flexible material, pressing means held from movement in the line of feed, a creaser, a folder, and means for moving the creaser and folder backward along the edge of the material and in contact therewith to form a fold, and for moving the creaser and folder forward to present the fold to the pressing means.

35 4. A machine of the class described, having, in combination, a support for a piece of flexible material, a member movable back and forth in the direction of the feed, a combined upper feed member and creaser and a folder both carried by said movable member, a lower feed member, means for raising and lowering said last-named member intermittently, and means for causing said last-named member to reciprocate with

45 said creaser and folder.

5. A machine of the class described, having, in combination, a support for a piece of flexible material, a member movable backwardly and forwardly in the direction of the feed, a combined upper feed member and creaser and a folder both carried by said movable member, a lower feed member, means for raising and lowering said last-named member intermittently, means for

causing said last-named member to reciprocate with said creaser and folder, and pressing means located in the rear of the folder.

6. A machine of the class described, having, in combination, a support for a piece of flexible material, a slide, means for reciprocating the slide in the line of feed, means for varying the extent of the reciprocating movements, a folder and feeding means carried by the slide, and fold pressing means adapted to hold the material stationary during the backward movement of the slide.

7. A machine of the class described, having, in combination, a support for a piece of flexible material, a hammer and an anvil held from movement in the line of feed, means for feeding the material intermittently past said hammer and anvil, a plow movable back and forth in the line of feed, and means for varying the extent of the intermittent feed movements during the operation of the machine, the construction and arrangement being such that the forward limit of the intermittent movements of the feeding means and plow is always the same.

8. A machine of the class described, having, in combination, a support for a piece of flexible material, a fold presser, a folder movable along the edge of the material to form the fold, a slitting knife located between the folder and the presser, and means for operating the presser, folder and knife.

9. A machine of the class described, having, in combination, a support for a piece of flexible material, a fold presser held from movement in the line of feed, a folder movable along the edge of the material to form the fold, a slitting knife located between the folder and the presser, and means for operating the presser, folder and knife.

10. A machine of the class described, having a combination, a support for a piece of flexible material, a slide, a folder fast to the slide, a feed member pivoted to the slide, means for raising and lowering the feed member, a second feed member arranged to 100 coöperate with the first mounted on the slide and held from vertical movement with respect thereto, means for reciprocating the slide, a fold presser, and means for operating the fold presser.

In testimony whereof I have signed my name to this specification.

PERLEY R. GLASS.
